UNITED STATES PATENT OFFICE.

FRANK M. MORTON, OF PHOENIX CITY, ALABAMA.

CALENDER RACK.

Application filed October 11, 1926. Serial No. 140,987.

The invention relates to improvements in calender racks of the general type disclosed in my U. S. Patent No. 1,495,920, of May 27, 1924.

5 The patented structure embodies a rack, a lap pin bearing head having a longitudinally slidable connection with said rack, inter-engageable elements on the rack and head to operatively connect them and normally prevent the head from sliding upon the rack, and yieldable means to normally hold said elements in engagement, said means being releasable when greater than normal pressure is applied to the head. 10 means are also provided in said patented structure, for releasing the yieldable means to permit manual return of the head to its normal position, after said head has been shifted along the rack by abnormal strain, 15 said means then serving to again stress said yieldable means to place it in condition to again function. If the yieldable means was not set at the proper strength, it would not properly function, and it is one object of 20 the present invention to provide a novel relation of parts whereby said yieldable means may be easily set only at the proper strength.

Another object is to provide a new and 25 improved construction, in which novel provision has been made for insuring proper positioning of the head relative to the rack, when said head is returned upon said rack, after pressure-effected sliding of the head.

30 With the foregoing in view, the invention resides in the novel subject matter hereinafter described and claimed, the description being supplemented by the accompanying drawing.

35 Fig. 1 is a perspective view of the improved calender rack.

Fig. 2 is a vertical sectional view thereof.

The numeral 3 designates a rack whose lower end is provided with the usual teeth 4 for coaction with the well known means on a machine with which the rack is used. Near its upper end, this rack is provided with a downwardly facing shoulder 5 and at an elevation below this shoulder, the rack 50 is formed with an upwardly facing shoulder 6, the two shoulders being disposed at opposite edges of the rack.

A lap pin bearing head 7, having the usual rollers 8 for engagement with the lap pin, is engaged with the upper end of the rack 3, said head being provided with a

vertical guide 9 which normally surrounds the portion of the rack between the shoulders 5 and 6, the ends of said guide then engaging the shoulders, as shown. The upper end 10 of the guide 9 is preferably chilled or hardened for co-action with shoulder 5 and this shoulder may be similarly treated.

60 The head 7, as in the patented structure, embodies a horizontally projecting guide 11, in which a plunger 12 and a coiled spring 13 are housed, movement of the plunger entirely out of the guide 11, being prevented by the set screw 14. The outer end of the 70 spring 13 engages a shoe 15 which abuts the inner end of a screw 16, the latter being threaded through the outer end of the guide 11. The outer end of this screw is provided with the equivalent 17 of a hand wheel, and this member 17 embodies a hub 18, between which and the guide 11, an ordinary lock washer 19 may be located. When the screw 16 is tightened to the limit permitted by the 75 hub 18, the spring 13 is placed under the proper compression to insure perfect operation of the device. When the spring is stressed to this extent, if undue upward force should be exerted upon the head 7 by 80 the lap pin, this head will laterally cant upon the rack 3, permitting disengagement of the shoulder 10 from the shoulder 5 and allowing upward sliding of the head upon the rack, so that no injury to any parts 85 will result. When the machine attendant overcomes the difficulty which has caused 90 release of the head 7 and wishes to return this head to its normal working position, he loosens the screw 16 until the head may either drop by gravity or be easily moved 95 to its lowered position, at which position, it encounters the shoulder 6, which properly locates it with respect to the rack bar. Then, upon again tightening the screw 16 and consequent stressing of the spring 13, 100 the plunger 12 is so projected as to engage the rack 3 and cause tilting of the guide 9 again to the operative position shown in Fig. 2, at which position the shoulders 5 and 10 contact with each other. The screw 16 is tightened to the limit permitted by the hub 18 and as this limit is invariable, it is insured that the spring 13 may have no more than the proper amount of stress imparted to it.

105 Thus, there is no danger of the device failing to trip when it should do so.

As excellent results have been obtained from the details disclosed, they are preferably followed. However, within the scope of the invention as claimed, variations may 5 be made.

I claim:—

1. A device of the class described comprising a rack, a lap pin bearing head having a longitudinally slidable connection 10 with said rack, inter-engageable elements on the rack and head to operatively connect them and to normally prevent said head from sliding upon the rack, yieldable means to normally hold said elements in engagement, said means being releasable when abnormal pressure is applied to said head, manual means for stressing said yieldable means to place it in condition to function, and invariable means for limiting the movement 15 of said stressing means, insuring that it shall impart no more than predetermined strength to said yieldable means.

2. A structure as specified in claim 1; said head having a guide transverse to the 25 rack, said yieldable means embodying a spring within said guide, said stressing means consisting of a manually operable screw threaded through the outer end of said guide, said limiting means consisting 30 of a shoulder on the screw for co-operation with the outer end of said guide, said shoulder having fixed invariable relation with said screw.

3. A device of the class described comprising a rack having a shoulder at one 35 edge facing in one direction and a longitudinally spaced shoulder at its other edge facing in the opposite direction, a lap pin bearing head having a guide receiving the portion of the rack between said shoulders 40

and having its ends engaged with the latter, said guide being of greater width than said rack to permit lateral canting thereon allowing the guide to clear the first named shoulder, spring means carried by said head and engaging said other edge of the rack to relatively position the rack and head and hold said guide engaged with both shoulders until abnormal pressure is exerted on said head, said spring means then permitting the aforesaid canting of the head and sliding thereof away from the second shoulder, and manually operated means for releasing said spring means to allow the head to easily return into engagement with said second shoulder, said manually operated means then serving to again stress said spring means to place it in operative condition, and by so doing serving to tilt the head to its original position at which it again engages the first named shoulder.

4. A device of the class described comprising a rack, a lap pin bearing head movably connected with said rack, interchangeable elements on the rack and head to operatively connect them and to normally prevent said head from moving with respect to the rack, yieldable means to normally hold said elements in engagement, said means being releasable when abnormal pressure is applied to said head, manual means for stressing said yieldable means to place it in condition to function, and invariable means for limiting the movement of said stressing means, insuring that it shall impart no more than predetermined strength to said yieldable means.

In testimony whereof I have hereunto affixed my signature.

FRANK M. MORTON.
